CLAIM

The ornamental design for a broadhead as shown and described.

DESCRIPTION

FIG. 1 is a top perspective view of a first embodiment of a broadhead;

FIG. 2 is a bottom perspective view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a right elevation view thereof; and

FIG. 8 is a left elevation view thereof.

FIG. 9 is a top perspective view of a second embodiment of a broadhead;

FIG. 10 is a bottom perspective view thereof;

FIG. 11 is a front elevation view thereof;

FIG. 12 is a rear elevation view thereof;

FIG. 13 is a top plan view thereof;

FIG. 14 is a bottom plan view thereof;

FIG. 15 is a right elevation view thereof; and,

FIG. 16 is a left elevation view thereof.

The broken lines shown represent unclaimed subject matter and form no part of the claimed design.
